US00D478286S

(12) **United States Design Patent** (10) Patent No.: **US D478,286 S**
Futral et al. (45) Date of Patent: **** Aug. 12, 2003**

(54) **PLASTIC BOTTLE**

(75) Inventors: **Daniel M. Futral**, Marietta, GA (US);
Brian D. Tyree, Douglasville, GA (US); **Michael L. Vaughn**, Marietta, GA (US)

(73) Assignee: **Ball Corporation**, Broomfield, CO (US)

(**) Term: **14 Years**

(21) Appl. No.: **29/152,601**

(22) Filed: **Dec. 21, 2001**

(51) LOC (7) Cl. **09-01**

(52) U.S. Cl. **D9/500**

(57) **CLAIM**

We claim the ornamental design for a plastic bottle, as shown and described.

DESCRIPTION

FIG. 1 is a front perspective view of a plastic bottle showing the present invention.

FIG. 2 is a side elevation view of the bottle shown in FIG. 1, all sides being identical.

FIG. 3 is a plan view from the top of FIG. 2; and, FIG. 4 is a plan view from the bottom of FIG. 2.

The broken line showing in the drawings is for illustrative purposes only and forms no part of the claimed design.
